ALEXANDER M. READ, OF COLUMBUS, OHIO.

PULVERIZING MACHINE.

Application filed December 31, 1919, Serial No. 348,506. Renewed February 28, 1924.

The present invention relates to certain new and useful improvements in pulverizing machines of the class in which each consists of a rotatable barrel wherein the material to be pulverized may be tumbled about with freely movable crushing bodies and be pulverized by contact therewith.

The present application is a continuation in part of my application, Serial No. 168,512, filed May 14, 1917.

The especial object of my invention is to provide a machine of the class described having improved arrangement of parts whereby the finished product will be promptly removed from the pulverizing chamber thereby increasing the effectiveness of the action upon the material remaining within the machine.

Another object is to provide a machine of the class described wherein the barrel is divided into a series of pulverizing chambers and is provided with improved means to classify the material relative to the dimensions of its constituent fragments, each chamber being provided with grinding bodies of a size appropriate to the most efficient treatment of the material in said chamber.

The devices by which I attain these objects are fully set forth in the following specification and illustrated in the accompanying drawings of which

Fig. 1 is a vertical longitudinal section of the preferred embodiment of my invention.

Figs. 2 and 3 are vertical longitudinal sections of two permissible modifications of the device illustrated in Fig. 1.

Like numerals refer to similar parts in the several figures.

As shown in the drawings the numeral 1 indicates a barrel adapted to revolve about its longitudinal axis. The form of the barrel 1 is subject to wide variation. It may be conical, as shown in Figs. 1 and 3 the cone having any preferred relation of base to altitude, or it may have parallel sides as shown in Fig. 2, its cross section being either cylindrical or prismatic. The axis of the barrel is so related to the horizontal that its lower side has a downward inclination sufficient to cause the included material to travel from the inlet, at one end, to the outlet at the other end in a predetermined time as the barrel revolves. To the barrel 1 is attached the bearing rings 2 and 3 which bear upon the rollers 4 and 5 to support the barrel for rotation. The rollers 4 and 5 are mounted in suitable

journal bearings 6 and 7 which are supported upon the foundations of the mill. To the barrel 1 is attached a ring gear 8 which is engaged by a pinion 9. The pinion 9 is mounted upon a power shaft from which power is derived to revolve the barrel. The upper end of the barrel 1 is closed by a plate 10 to which is secured a cylindrical extension 11. The extension 11 is journaled in a pillow block 12 supported upon the foundation casting 13. The pillow block 12 is provided with the customary removable cap 14 in which is formed a lubricant receptacle 15. 16 is a ball bearing interposed between the outer end of the pillow block 12 and the flange 17 of the cylindrical extension 11 to prevent longitudinal movement of the barrel. The cylindrical extension 11 and the plate 10 are pierced by a central bore through which extends a cylindrical trough 18 formed at the lower end of a feed hopper 19. Positioned within the cylindrical trough 18 is a screw conveyer 20 to the extended shaft of which is attached a suitable pulley 21 adapted to be connected with any convenient source of power to rotate the screw conveyer 20 and thereby transfer material from the feed hopper 19 to the interior of the barrel 1. The lower end of the barrel 1 is closed by a transverse screen 22 provided with screening apertures adapted to permit the escape of the fully pulverized material from the interior of the mill while retaining the oversize material for further grinding. The screen 22 is preferably of conical form having its apex in the axis of revolution of the barrel 1 and its concave side towards the advancing material. Experience has demonstrated that screens of this form are more efficient than the curved screens, shown in Fig. 2, or the flat screens shown in Fig. 3, although either of these forms may be used without departure from the spirit of my invention. The size, form, and arrangement of the screening apertures are subject to wide variation to suit the requirements of materials of different character and the desired fineness of the product. These apertures preferably expand outwardly to prevent the lodgment therein of fragments of material and the consequent choking of the screen.

As the fineness of grinding is directly related to the duration of time the fragments of material are retained within the mill, I prefer to form the barrel 1 with such a taper

- that when mounted upon a horizontal axis, as shown in Fig. 1, the rate of flow of the material longitudinally of the mill will carry said material to the discharge end at the precise moment it is pulverized to the desired degree of fineness. It is apparent that if the taper of the mill were increased it might be necessary to incline the axis of rotation upwardly to prevent the material flowing too rapidly through the mill, and if the sides of the barrel were made less tapering, or parallel as shown in Fig. 2, it would become necessary to incline the axis downwardly to produce the desired rate of travel.
15. The friction of the material against the sides of the barrel cause the lower part of the mass to move upwardly with the ascending side of the barrel, while the upper portion of the mass slides downward, maintaining a continuous orbital movement of the fragments of which the mass is composed, and the friction due to this movement is an important element in producing the grinding action of the mill. The grinding balls, being of greater
20. specific gravity than the fragments of the material which is being pulverized, gravitate toward the lower part of the mass and become buried beneath the lighter material. These balls are carried upward with the side
25. of the barrel to an elevation depending upon the angle of repose which is characteristic to the material under treatment, and to the centrifugal force due to the velocity of rotation. At the point of maximum elevation the material falls away from the side of the barrel and the grinding balls roll upon the surface of the mass, striking fragments of material lying upon the lower side of the barrel to break them by their percussive action, thereby
30. materially assisting in pulverizing the material.

When a mass composed of freely movable fragments of various size but of the same specific gravity is agitated, the finer particles tend to slip through the interstices between the larger fragments, and the larger fragments tend to float to the surface, resulting in a more or less complete stratification of the mass relative to the size of its component fragments. Due to this tendency to stratification, and the inclination of the lower side of the barrel, the finer particles of material sift to the bottom of the mass and travel longitudinally of the mill tending to accumulate against the surface of the screen. Owing to the slippage of material against the surfaces of the mill this accumulation of fine material slides across the screening apertures as the mass is carried upwardly and the smaller fragments are forced through these apertures by the weight of material upon them. From the point of maximum elevation the material rolls downwardly, striking the surface of the screen along lines approximately normal thereto, and small fragments are carried

through the screening apertures without change of direction.

By the peculiar construction of the screening partitions 22, 23, 24 and 25 the portion of each screening surface in contact with the material which is to be screened is so inclined to the horizontal as to accomplish the most efficient screening action. Due to this inclination of the screens the material slides across its surface, the finer particles passing through the screening apertures, and the larger fragments sliding to the bottom of the screening surface to mingle with the ascending mass of material lying upon the bottom surface of the barrel. From the point of its maximum elevation the material adjacent the screen rolls downwardly striking the surface of the screen along lines approximately normal thereto, and small fragments are carried through the screening apertures without change of direction. At the same time the larger and heavier fragments, together with the grinding balls, striking upon the surface of the screen, produce vibrations therein which effectively prevent the clogging of the screen.

The barrel 1 is divided into a series of compartments A, B, C and D, by transverse screens 23, 24 and 25 which are similar to the screen 22 but are respectively provided with apertures of progressively decreasing dimensions, the screen nearest the receiving end having the largest aperture. By this arrangement of screens the material in the successive compartments of the mill is classified relative to the size of its component fragments, and each grinding compartment is provided with grinding balls of a size appropriate to the most efficient grinding of the material in said compartment. Although the best results have been obtained with conical screens, such as are illustrated in Fig. 1, I do not limit myself to this construction, and screens of other forms, such as the spherical curvature shown in Fig. 2, or the flat screens shown in Fig. 3, may be used without departure from the spirit of my invention. However, the use of conical or curved screens is preferred to flat screens because of their greater screening capacity. During the rotation of the mill the cascading material at the forward end of each of the compartments B, C and D, impinges upon the convex rearward surfaces of the screens 23, 24 and 25 respectively, and is deflected rearwardly in the mill, producing a vortex behind the lower portion of each screen such as is indicated at a, b and c, leaving the larger portion of the lower half of the screen unobstructed, and thereby facilitating the rapid transfer of the fine material from each compartment to the next succeeding compartment. By the peculiar arrangement of parts above described there is presented to the advancing material, inclined screening surfaces arranged for the

most efficient screening action, which are unobstructed by the accumulation of material against their lower sides.

As the fragments become more completely

5 sub-divided a given weight of material acquires greater bulk and the conical form of the barrel 1 gives to the respective grinding compartments a progressively increasing capacity which permits the uniform loading

10 of the mill from end to end.

E is a receiving chamber, 26, the walls 27 of which fit about the outside of the discharge end of the barrel to form a dust tight joint therewith and prevent the escape of the finely 15 divided material into the surrounding atmosphere. A spout 28, is provided through which the material may escape from the receiving chamber to be disposed of in any preferred manner.

20 What I claim is:

1. In a pulverizing mill, an approximately horizontal rotatable barrel containing a multiplicity of freely movable crushing bodies and having its lower side so inclined that 25 the included material will travel thereon from one end to the other as the barrel revolves, feeding means to introduce material to be pulverized at one end of the barrel, and a transverse screen concave on the side to 30 wards the feeding means dividing the interior of the barrel.

2. In a pulverizing mill, an approximately horizontal rotatable barrel containing a multiplicity of freely movable crushing bodies 35 and having its lower side so inclined that the included material will tend to travel thereon from one end to the other as the barrel revolves, feeding means to introduce material to be pulverized at one end of the barrel, and a transverse screen convex on the side opposite the feeding means dividing the interior of the barrel.

3. In a pulverizing mill, an approximately horizontal barrel containing a plurality of 45 freely movable crushing bodies and having its lower side so inclined that the included material will travel thereon from one end to the other as the barrel revolves, feeding means to introduce material to be pulverized 50 at one end of the barrel, and a transverse screen concave on the side towards the feeding means and convex on the opposite side dividing the interior of the barrel.

4. In a pulverizing mill, an approximately 55 horizontal rotatable barrel containing a multiplicity of freely movable crushing bodies and having its lower side so inclined that the included material will travel thereon from one end to the other as the barrel revolves, feeding means to introduce material to be 60 pulverized at one end of the barrel, and a plurality of transverse screens concave on the side towards the feeding means dividing the interior of the barrel into a succession of pulverizing chambers.

5. In a pulverizing mill, an approximately horizontal rotatable barrel containing a multiplicity of freely movable crushing bodies and having its lower side so inclined that the included material will tend to travel thereon from one end of the barrel to the other as the barrel revolves, feeding means to introduce material to be pulverized at one end of the barrel, and a plurality of transverse screens concave on the side towards the feeding 70 means dividing the interior of the barrel into a succession of pulverizing chambers the successive screens being provided with screening apertures of progressively decreasing dimensions adapted to pass the material as it is 75 progressively pulverized.

6. In a pulverizing mill, an approximately horizontal rotatable barrel containing a multiplicity of freely movable crushing bodies and having its lower side so inclined that the included material will tend to travel thereon from one end to the other as the barrel revolves, feeding means to introduce material to be pulverized at one end of the barrel, and a plurality of transverse conical screens dividing the interior of the barrel into a succession of pulverizing chambers said screens being adapted to effect the classification of the included material relative to 80 its size of component fragments.

7. In a pulverizing mill, an approximately horizontal rotatable barrel containing a multiplicity of freely movable pulverizing bodies and having its lower side so inclined that the included material will tend to travel 85 thereon from one end to the other as the barrel revolves, feeding means to introduce material to be pulverized at one end of the barrel, and a transverse screen concave on the side towards the advancing material closing 90 the other end of the barrel adapted to retain the crushing bodies and over sized material while permitting the escape of the fully pulverized material.

8. In a pulverizing mill, an approximately 100 horizontal barrel containing a plurality of freely movable crushing bodies and having its lower side so inclined that the included material will tend to travel thereon from one end to the other as the barrel revolves, means to introduce material to be pulverized at one end of the barrel, and a transverse conical screen closing its lower end and adapted 105 to retain the crushing bodies and oversized material while permitting the escape of the fully pulverized material.

9. In a machine of the class described, the combination with a conical barrel adapted to revolve about its longitudinal axis which is so disposed to the horizontal that the lower side of said barrel will have such downward inclination that the included material will tend to travel thereon from the smaller to the larger end as the barrel revolves, of a 115 multiplicity of freely movable crushing 120 bodies.

bodies within the barrel, means to introduce material to be pulverized at the smaller end of the barrel, and a transverse conical screen closing its larger end and adapted to retain the crushing bodies and oversize material while permitting the escape of the fully pulverized material.

10. In a machine of the class described, the combination with a conical barrel adapted to revolve about its longitudinal axis which is so disposed to the horizontal that the lower side of said barrel will have such downward inclination that the included material will tend to travel from the smaller to the larger end as the barrel revolves, of a multiplicity of freely movable crushing bodies within the barrel, means to introduce material to be pulverized at the smaller end of the barrel, a transverse conical screen closing its larger end and adapted to retain the crushing bodies and the oversize material while permitting the escape of fully pulverized material, and means to classify the material longitudinally of the mill relative to its component fragments.

11. In a machine of the class described, the combination with a conical barrel adapted to revolve about its longitudinal axis which is so disposed to the horizontal that the lower side of said barrel will have such downward inclination that the included material will tend to travel thereon from the smaller to the larger end as the barrel revolves, of a multiplicity of freely movable crushing bodies within the barrel, means to introduce material to be pulverized at the smaller end of the barrel, and means at the larger end to remove the fully pulverized material while retaining the crushing bodies and oversize material within the barrel.

12. In a machine of the class described, the combination with a conical barrel adapted to revolve about its longitudinal axis which is so disposed to the horizontal that the lower side of the said barrel will have such downward inclination that material within the barrel will tend to travel thereon from the smaller to the larger end as the barrel revolves, of a multiplicity of freely movable crushing bodies within the barrel, means to introduce material to be pulverized at the smaller end of the barrel, and a plurality of transverse screens dividing the interior of the barrel into a succession of pulverizing chambers and adapted to permit the progression of the fine material while retaining the crushing bodies and oversize material in each successive chamber.

13. In a pulverizing mill of the class described, the combination of an approximately horizontal rotatable barrel containing a multiplicity of freely movable crushing bodies and having its lower side downwardly inclined from the receiving to the discharge end of the barrel, means to introduce mate-

rial to be pulverized at the receiving end of the barrel, a transverse partition dividing the interior of the barrel to confine said grinding bodies between predetermined transverse planes, and provided with screening perforations in its peripheral part adapted to permit the passage of fine material said partition being positioned and arranged so as to engage the material and grinding bodies adjacent the rearward side of said partition and deflect them to lines transversely from and longitudinally in advance of the lines of their normal descent.

14. In a pulverizing mill of the class described, the combination with an approximately horizontal rotatable barrel containing a multiplicity of freely movable crushing bodies and having its lower side downwardly inclined from the receiving to the discharge end of the barrel, means to introduce material to be pulverized at the receiving end of the barrel, a transverse partition dividing the interior of the barrel to confine said grinding bodies between predetermined transverse planes, and provided with screening perforations in its peripheral parts adapted to permit the passage of fine material, said partitions being positioned and arranged to engage with the material and grinding bodies adjacent the rearward side of said partitions after they have been raised by the rotation of the barrel and cause them to descend in transverse planes other than the planes in which they were raised so as to form a clearance chamber adjacent the lower part of said partition communicating with the aforesaid screening perforations.

15. In a pulverizing mill of the class described, the combination of an approximately horizontal rotatable barrel containing a multiplicity of freely movable crushing bodies and having its lower side downwardly inclined from the receiving to the discharge end of the barrel, means to introduce material to be pulverized at the receiving end of the barrel, and a transverse partition dividing the interior of the barrel to confine said grinding bodies between predetermined transverse planes and provided with screening perforations adapted to permit the passage of fine material said partition being arranged to engage the material and grinding bodies at the end of the chamber after they have been raised by the rotation of the barrel and deflect them to lines transversely remote from and longitudinally in advance of the lines of their normal descent.

16. In a pulverizing mill of the class described, the combination of an approximately horizontal rotatable barrel containing a multiplicity of freely movable crushing bodies and having its lower side downwardly inclined from the receiving to the discharge end of the barrel, means to introduce material to be pulverized at the receiving end of the bar-

- 7 rel, and a transverse wall dividing the interior of the barrel provided with screening apertures adapted to permit the passage of fine material while retaining the grinding bodies and oversize material, the screening part of said wall being so inclined to vertical transverse planes when in operation that it will partly support the mass of material in the chamber and facilitate the passage of 10 fine material through the screening apertures.
17. In a pulverizing mill of the class described, the combination of an approximately horizontal rotatable barrel containing a multiplicity of freely movable crushing bodies, 15 means to introduce material to be pulverized at one end of the barrel, a transverse partition dividing the interior of the barrel and provided with screening perforations in its peripheral part adapted to permit the passage 20 of fine material, and means operative as the barrel revolves to deflect the material and grinding bodies adjacent the rearward side of the screen to lines transversely remote from and longitudinally in advance of the 25 lines of their normal descent.
18. In a pulverizing mill, an approximately horizontal rotatable barrel containing a multiplicity of freely movable crushing bodies and having its lower side so inclined 30 to the horizontal that the included material will tend to flow thereon from its higher toward its lower end as the barrel revolves, and a plurality of walls spaced longitudinally of the barrel and extending transversely 35 thereof, said walls dividing the barrel into a plurality of crushing chambers and progressively increasing in area from the higher toward the lower end, the walls being inclined to the adjacent portion of the sides of 40 the barrel and toward the lower end thereof so that together with the sides of the barrel they afford rotary supports for the material and being provided with screening apertures adapted to pass the pulverized material.
- 45 19. In a pulverizing mill, an approximately horizontal rotatable barrel containing a plurality of freely movable crushing bodies and having its lower side inclined to the horizontal so that the crushing bodies will 50 tend to flow thereon from its higher toward its lower end as the barrel revolves, and a plurality of walls extending transversely of the barrel and dividing its interior into a series of chambers, said walls progressively 55 increasing in area from the higher toward the lower end of the barrel and being concave on the side towards the advancing material, the walls being provided with perforations for the passage of pulverized material.
- 60 20. In a pulverizing mill, an approximately horizontal rotatable barrel containing a multiplicity of freely movable crushing bodies and having its lower side inclined to the horizontal so that the included material 65 will tend to flow thereon from its higher to- ward its lower end as the barrel revolves, and a plurality of walls spaced longitudinally of the barrel and extending transversely there- 70 of, said walls forming a plurality of crushing chambers and progressively increasing in diameter from the higher toward the lower end, the walls being concave on the side toward the advancing material and being provided with screening apertures adapted to pass the pulverized material. 75
21. In a pulverizing mill, an approximately horizontal rotatable barrel containing a multiplicity of freely movable crushing bodies and having its lower side inclined to the horizontal so that the crushing bodies 80 will tend to flow thereon from its higher toward its lower end as the barrel revolves, a wall extending transversely of the barrel and having the side towards the advancing material concave, said wall being provided with screening apertures adapted to pass the pulverized material and being so inclined to the vertical that together with the sides of the barrel it affords a rotary support for the material. 85
22. In a pulverizing mill, a barrel rotatable about its longitudinal axis and having its lower side inclined to the horizontal so that the material therein will travel thereon from one end toward the other as the barrel revolves, a wall extending transversely of the barrel to form a crushing chamber and provided with a plurality of screening apertures, a multiplicity of freely movable crushing bodies in said chamber, said wall being inclined to the axis of the barrel whereby together with the sides of the barrel it affords a rotary support for the material as the latter is subjected to the action of the crushing bodies in said chamber and passes the material as it is pulverized. 90
23. In a pulverizing mill, an approximately horizontal rotatable barrel containing a multiplicity of freely movable crushing bodies and having its lower side inclined to the horizontal so that the included material will flow thereon from its higher toward its lower end as the barrel revolves, a wall extending transversely of the barrel and having its face toward the advancing material 95 inclined with respect to the adjacent portion of the sides of the barrel and toward the lower end thereof so that the wall serves together with the sides of the barrel to afford a rotating support for the material, said wall being provided with a plurality of screening apertures to pass the pulverized material. 100
24. In a pulverizing mill, an approximately horizontal rotatable barrel containing a multiplicity of freely movable crushing bodies and having its lower side inclined to the horizontal so that the included material will flow thereon from its higher toward its lower end as the barrel revolves, a wall extending transversely of the barrel to divide 105 110 115 120 125 130

- the interior thereof into a plurality of chambers and having its face toward the advancing material inclined with respect to the axis of the barrel whereby the wall serves together with the sides of the barrel to afford a rotating support for the material, said wall being provided with a plurality of screening apertures to pass the pulverized material.
25. A pulverizing mill comprising a substantially horizontal barrel containing a multiplicity of freely moving crushing bodies and a screening wall extending across said barrel having a concave surface toward the advancing material, said wall serving together with the barrel to support the crushing bodies and material within the barrel.
26. A pulverizing mill comprising a substantially horizontal barrel containing a multiplicity of freely moving crushing bodies and a screening wall extending across said barrel having a concave surface toward the advancing material, said wall serving together with the barrel to support the crushing bodies and material within the barrel and forming an inclined surface up which the material travels in its passage through the barrel.
27. In a pulverizing mill, an approximately horizontal rotatable barrel containing a multiplicity of freely movable crushing bodies and having inclined sides so disposed that the said crushing bodies will flow in lines inclined to the axis of rotation of the barrel, a wall extending transversely of the barrel and having the side towards the advancing material concave and approximately normal to the lines of flow of the crushing bodies, said wall being provided with screening apertures adapted to pass the pulverized material.
28. In a pulverizing mill, an approximately horizontal rotatable barrel containing a plurality of freely movable crushing bodies and having inclined sides so disposed that the crushing bodies will flow in lines inclined to the axis of rotation of the barrel, a plurality of walls extending transversely of the barrel and dividing its interior into a series of chambers of progressively increasing area, the sides of said walls towards the advancing material being concave and approximately normal to the lines of flow of the material within the barrel, each of said walls having perforations for the passage of pulverized material.
29. In a pulverizing mill, an approximately horizontal rotatable conical barrel containing a plurality of freely movable crushing bodies, means to introduce material to be pulverized at the small end of the barrel, and a plurality of walls extending transversely of the barrel dividing its interior into a series of progressively increasing chambers, said walls being positioned as described relatively to the barrel wall to provide for the material in each chamber two rotating supports inclined oppositely to each other and to the horizontal, said walls having apertures to permit the flow therethrough of material from the superposed mass.
30. In a pulverizing mill, an approximately horizontal rotatable conical barrel containing a plurality of freely movable crushing bodies, means to introduce material to be pulverized at the small end of the barrel, and a conical wall at the large end of the barrel having its concave face turned toward the smaller end of the barrel and positioned to have below the material a rotary support inclined to the horizontal and provided with apertures to permit the escape therethrough of pulverized material.
31. In a machine of the class described, the combination with a conical barrel adapted to rotation about its longitudinal axis which is so disposed to the horizontal that the lower side of said barrel will have such downward inclination that the included material will tend to travel thereon longitudinally of the mill as the barrel revolves, of a multiplicity of freely movable crushing bodies within the barrel, means to introduce material to be pulverized at the upper end of the barrel, and a transverse conical wall closing the lower end of the barrel and provided with a zone of screening apertures adapted to permit the escape of the fully pulverized material while retaining the crushing bodies and oversize material.
32. In a machine of the class described, the combination with a conical barrel adapted to rotation about its longitudinal axis which is so disposed to the horizontal that the lower side of the barrel will have such downward inclination that the included material will tend to travel thereon longitudinally of the mill as the barrel revolves, of a multiplicity of freely movable crushing bodies within the mill, means to introduce material to be pulverized at the upper end of the barrel, and a plurality of transverse conical walls dividing the interior of the barrel into a succession of pulverizing chambers, each wall being provided with a zone of screening apertures which permit the progression of fine material while retaining the crushing bodies and oversize material within the respective pulverizing chambers.
33. In a machine of the class described, the combination with a conical barrel adapted to rotation about its longitudinal axis which is so disposed to the horizontal that the lower side of the barrel will have such downward inclination that the included material will tend to travel thereon longitudinally of the mill as the barrel revolves, of a multiplicity of freely movable crushing bodies within the barrel, means to introduce material to be pulverized at the upper end of the barrel, and a plurality of transverse conical walls dividing the interior of the barrel into a succession of pulverizing chambers, said walls being provided with screening apertures adapted to ef-

fect the classification of the material included within the respective chambers relative to the size of its component fragments.

34. In a machine of the class described, the combination with a conical barrel adapted to rotation about its longitudinal axis which is so disposed to the horizontal that the lower side of the barrel will have such downward inclination that the included material will 5 tend to travel thereon longitudinally of the mill as the barrel revolves, of a multiplicity of freely movable crushing bodies within the barrel, means to introduce material to be pulverized at the upper end of the barrel, and a 10 plurality of transverse conical walls dividing the interior of the barrel into a succession of pulverizing chambers of progressively increasing capacity, said walls being provided with screening apertures adapted to effect the 15 classification of the material included within the respective chambers relative to the size of its component fragments.

35. In a pulverizing mill, an approximately horizontal rotatable barrel containing a 25 multiplicity of freely movable crushing bodies and having inclined sides so disposed that the said crushing bodies will tend to flow thereon from its higher towards its lower end as the barrel revolves a wall extending 30 transversely of the barrel and having the side towards the advancing material concave, said wall being provided with screening apertures adapted to pass the pulverized material.

36. In a pulverizing mill, an approximately 35 horizontal rotatable barrel containing a plurality of freely movable crushing bodies and having inclined sides so disposed that the crushing bodies will tend to flow thereon from its higher towards its lower end as the 40 barrel revolves, a plurality of walls extending transversely of the barrel and dividing its interior into a series of chambers of progressively increasing area, said walls being concave on the side towards the advancing 45 material and provided with perforations for the passage of pulverized material.

37. In a pulverizing mill, an approximately 50 horizontal rotatable conical barrel containing a multiplicity of freely movable crushing bodies, means to introduce material to be pulverized at the smaller end of the barrel, a transverse wall closing the larger

end of the barrel and having a concave face towards the smaller end of the barrel, said 55 wall being positioned to afford a rotary support below the material which is inclined to the horizontal and provided with apertures adapted to permit the escape therethrough of fully pulverized material.

38. In a pulverizing mill, an approximately 60 horizontal rotatable conical barrel containing a multiplicity of freely movable crushing bodies, means to introduce material to be pulverized at the smaller end of the barrel, a 65 plurality of transvers walls dividing the interior of the barrel, each having a concave face towards the smaller end of the barrel, said walls being positioned to afford rotary supports below the material which are inclined to the horizontal and provided with 70 apertures to permit the escape therethrough of fully pulverized material.

39. In a pulverizing mill, an approximately 75 horizontal rotatable barrel containing a multiplicity of freely movable crushing bodies and having inclined sides so disposed that the said crushing bodies will tend to flow thereon from the receiving towards the discharge end of the mill as the barrel revolves, a screen extending transversely of 80 the barrel and forming separate chambers each having crushing bodies therein, said screen being so disposed that it affords an inclined support upon which the material in the chamber at its upper side may slide as the 85 barrel revolves as and for the purpose set forth.

40. In a pulverizing mill, an approximately 90 horizontal rotatable barrel containing a multiplicity of freely movable crushing bodies and having inclined sides so disposed that the said crushing bodies will tend to flow thereon from the receiving towards the discharge end of the mill as the barrel revolves, 95 of a plurality of screens extending transversely of the barrel and forming separate chambers each having crushing bodies therein, each screen being so disposed that it affords an inclined support upon which the material in the chamber at its upper side may slide as the barrel revolves as and for the 100 purpose set forth.

In testimony whereof, I affix my signature.
ALEXANDER M. READ.
